UNITED STATES PATENT OFFICE

129,403

DESIGN FOR A BOTTLE HOLDER

William Sedgwick, Des Moines, Iowa, assignor to
C. E. Erickson Company Incorporated, Des
Moines, Iowa, a corporation of Iowa

Application December 11, 1940, Serial No. 97,260

Term of patent 7 years

To all whom it may concern:

Be it known that I, William Sedgwick, a citizen of the United States and a resident of Des Moines, in the county of Polk and State of Iowa, have invented a new, original, and ornamental Design for a Bottle Holder, of which the following is a specification, reference being had to the accompanying drawing, forming part thereof.

Figure 1 is a perspective view of a bottle holder, showing my new design.

Figure 2 is a top plan view thereof, on an enlarged scale.

Figure 3 is a front elevational view, and

Figure 4 is a vertical sectional view, on an enlarged scale, taken on the line 4—4 of Figure 3.

I claim:

The ornamental design for a bottle holder, substantially as shown.

WILLIAM SEDGWICK.
